L. W. SOUTHGATE,
PAPER WINDING MECHANISM,
APPLICATION FILED JUNE 28, 1912

Patented June 15, 1915.

FIG. 1.

UNITED STATES PATENT OFFICE.

LOUIS W. SOUTHGATE, OF WORCESTER, MASSACHUSETTS, ASSIGNOR TO AUTO PNEUMATIC ACTION COMPANY, A CORPORATION OF NEW YORK.

PAPER-WINDING MECHANISM.

1,142,988.

Specification of Letters Patent. Patented June 15, 1915.

Application filed June 28, 1912. Serial No. 706,383.

To all whom it may concern:

Be it known that I, Louis W. SOUTHGATE, a citizen of the United States, residing at Worcester, in the county of Worcester and State of Massachusetts, have invented a new and useful Paper-Winding Mechanism, of which the following is a specification.

The object of this invention is to provide a new and improved paper winding mechanism by which a web of paper can be accurately wound into a roll.

The device has been primarily designed for use in connection with the perforated note-sheets employed in musical instruments so that by accurate drawing forward and winding of said note-sheet the same can be kept in accurate registration with the tracker bar.

The best way now known to me for practising the invention is shown in the accompanying drawing in which,

Figure 1 is a front elevation of the spool box of a musical instrument showing my invention applied to the winding or take-up roll therein, Fig. 2 is an end elevation of one of the flanges on the take-up spool, Fig. 3 is a detail view on an enlarged scale illustrating the operation of the cam on said flange, and Fig. 4 is an enlarged view illustrating the operation of the throw-out connections.

Referring to the drawing and in detail, A designates the spool box and B—B the usual bearings in which can be placed a music spool or roll C upon which is wound a perforated note-sheet D.

E designates the usual tracker having music openings, which tracker is secured to the spool box.

10 The take-up spool mechanism is constructed as follows:—10 designates a shaft which is journaled in the spool box and on which the body F of the take-up spool is mounted and pinned thereto by a pin 11 so that the 15 take-up spool and said shaft turn as one piece. Secured on said shaft 10 is a gear 12. A supplemental frame or gear support 13 is secured to the spool box by studs or bushings. A shaft 14 is slidably journaled in the side of the spool box and in said frame 13 and carries a pinion 15 at its end which can mesh with the gear 12 on the shaft 10. The shaft 14 is provided with a sprocket wheel 16

at its end which is driven from the motor and a sprocket wheel 17 is loosely journaled on the 55 shaft 14 and connects by a sprocket chain 18 to a sprocket pinion 19 secured on the shaft of the right-hand journal B for the music roll. The sprocket wheel 17 carries a pin 20 set in position to be engaged by a pin 21 carried 60 by a grooved collar 22 secured on the shaft 14 engaging which is a pin projecting from a pivoted lever 23. A link 24 extends from the lever 23 to the usual rewind controlling finger lever. This gearing is of the ordinary or preferred arrangement and is so arranged that when in the position shown, the pinion 15 will drive the gear 12 and turn the music spool F in a direction which will draw the note-sheet D forward over the 70 tracker E and wind the same up upon said spool, so that when said lever 23 is thrown to the position indicated by dotted lines, the pinion 15 will be disengaged from the gear 12 and the pin 21 engaged with the pin 20, 75 whereby the music spool C will be rotated at a fast speed in a direction to draw the note-sheet back over the tracker and from the take-up spool F and rewind the same on the music spool.

As thus far described, the parts are of the usual or approved construction. The particular feature of the invention resides in the construction of the flanges on the take-up spool, which construction will now be 85 described. This construction is preferably duplicated at both ends of the take-up spool, the two flanges being rights and lefts. A description of the right-hand flange construction will give a clear understanding of 90 the invention.

Fitted on a cut-away portion at the end of the music spool is a flanged end piece 25 which is held to the music spool F by 95 screws 26.

G represents the music spool flange. The same has a relatively long hub 27 which is loosely fitted on the shaft 10 and which extends through the end piece 25 and into a hole or socket bored in the end of the take-up spool. A spring 28 is placed on this hub and has one end bearing on the end piece 25 and the other on a collar 29 secured on said hub 27. The end piece 25 is provided with projections 30 fitted into holes 31 100 cut in the end flange G. By this arrange- 105

ment the end flange G will have to turn with the spool F and the end flange can move axially independently of the spool F and is normally pushed in toward the spool 5 by the action of the spring 28.

The body of the spool is made of a length just a little less than the width of the note-sheet D and the flange is normally held away from engagement with the edge of the 10 note-sheet and from that portion of the note-sheet wound on the take-up spool, but is allowed to move inwardly for a short period during each rotation of the take-up spool to pat or adjust each convolution of the note- 15 sheet as it is wound on the take-up spool and thus insure a complete accurate winding. To accomplish this function, the take-up spool is provided with a recess or cam surface 32, engaging which is a screw 33 threaded in an arm 34 secured on a shaft 35. A check nut 330 is preferably mounted on the screw 33 so that the same can be kept in accurate adjustment. By reason of this 20 construction, as the flange and spool revolve, as the cam surface 32 comes opposite the screw 33 which forms an operating abutment, the flange will move inwardly toward the body of the take-up spool and will thus accurately adjust each convolution of the 25 note-sheet as it is wound on the spool and this action will take place for each revolution of the spool.

The construction is duplicated at the left-hand end of the spool, the shaft 10 in this 30 part of the structure being journaled in the spool box and secured inside of the spool. The cams on the two flanges G—G are preferably set in the same horizontal line so that they will act simultaneously, or together.

40 While I have shown the flange construction duplicated at each end of the take-up spool, it is to be understood, of course, that the broad invention contemplates the use of only one operating or movable flange, say 45 the right-hand flange. When this single flange arrangement is employed, the left-hand flange is made permanent or fixed and set in position just to engage the left-hand edge of the web.

50 The shaft 35 is extended through the right-hand side of the spool box and is provided with an arm 36 which connects by a link 37 to a lever 38 turning with, or formed as part of the lever 23. By this arrangement, when the lever 23 is shifted, the screws 33 will be swung outwardly and clear of the flanges G so that the flanges will close up to the note-sheet as the same is rewound on the music spool, and so that the operation 55 of adjusting each convolution, which takes place when the note-sheet is being wound up on the take-up spool, will not take place.

By this arrangement, by insuring accurate winding of the note-sheet on the take-up spool, the note-sheet can be kept in ac-

curate registration with the tracker during its forward run.

The music roll or the tracker may be provided with any of the usual adjusting mechanisms so that a correct initial relative position of the music sheet and the tracker can be obtained.

While the invention has been described as applied to a perforated note-sheet in a musical instrument, the same is capable of 75 broader application and can be used in other structures where it is desired to wind a web of paper accurately into a roll.

The details and arrangements herein shown and described may be greatly varied 80 by a skilled mechanic without departing from the scope of the invention as expressed in the claims.

Therefore, having fully described my invention, what I desire to secure by Letters- 85 Patent is:

1. In a paper winding mechanism, a winding or take-up spool, means movable axially thereof for adjusting or determining the position of the web as it is wound, and an 90 automatically operating cam mechanism for operating said means.

2. In a paper winding mechanism, a winding or take-up spool, means movable axially thereof for adjusting the position of the web 95 as it is wound, and an automatically operating cam for causing said means to act for each revolution of the winding or take-up spool.

3. In a paper winding mechanism, a winding or take-up spool, a flange movable axially thereof for adjusting or determining the position of the web as it is wound, and an automatically cam-operating mechanism 100 for operating said flange.

4. In a paper winding mechanism, a winding or take-up spool, a flange on said spool and axially movable thereof for adjusting or determining the position of the web as it 105 is wound, a cam formed in said flange, and an abutment engaging said cam.

5. In a paper winding mechanism, a winding or take-up spool, a flange on said spool and axially movable thereof for adjusting or determining the position of the web as it 11 is wound, a spring for forcing the flange in one direction, a cam on said flange, and an abutment engaging said cam.

6. In a paper winding mechanism, a winding or take-up spool, a flange turning therewith and movable axially thereof for adjusting or determining the position of the web as it is wound, a spring for forcing the flange toward the spool, a cam carried by 12 said flange, and an abutment engaging said flange.

7. In a paper winding mechanism, a winding or take-up spool, flanges mounted at each end thereof and axially movable there- 13 of and turning therewith for adjusting or

determining the position of the web as it is wound, a cam carried by each flange, and abutments engaging the cams.

8. In a paper winding mechanism, a winding or take-up spool, means movable axially thereof for adjusting or determining the position of the web as it is wound up on the spool, cam mechanism for operating said means; and connections for rendering said cam mechanism inoperative when the web is unwound from the take-up spool.

9. In a paper winding mechanism, a winding or take-up spool, a flange on said spool and movable axially thereof for adjusting or determining the position of the web as it is wound, cam mechanism for operating said flange, and means for rendering the cam mechanism inoperative when the web is unwound from the take-up spool.

10. In a musical instrument, the combination of a tracker, a take-up spool for the perforated note-sheet, a movable flange on the take-up spool, cam mechanism for operating said flange as the note-sheet is drawn forward over the tracker, and connections for rendering said cam mechanism inoperative when the music sheet is unwound from the take-up spool.

11. In a musical instrument, the combination of the tracker and take-up spool, means for holding a music spool in relation therewith so that the perforated note-sheet can coöperate with the tracker, gearing for rotating either the take-up spool to draw the

note-sheet over the tracker or to rotate the music spool to rewind the note-sheet on the music spool, movable flanges on the take-up spool, cam mechanism for operating said movable flanges, and connections constructed and arranged so that said cam mechanism will be operative when the take-up spool is driven and so that the same will be inoperative when the music spool is driven.

12. In a musical instrument, the combination of the tracker and take-up spool, means for holding a music spool in relation therewith so that the perforated note-sheet can coöperate with the tracker, gearing for rotating either the take-up spool to draw the note-sheet over the tracker or to rotate the music spool to rewind the note-sheet on the music spool, movable flanges mounted on the take-up spool, springs for forcing said flanges toward the center of the take-up spool, cam mechanism for operating said flanges, and means constructed and arranged so that said cam mechanism will be operative when the take-up spool is driven, and which will be inoperative when the music spool is driven and allow the flanges to remain in innermost position during rewinding.

In testimony whereof I have hereunto set my hand, in the presence of two subscribing witnesses.

LOUIS W. SOUTHGATE.
